UNITED STATES PATENT OFFICE.

PATRICK KEEGAN, OF FALL RIVER, MASSACHUSETTS, ASSIGNEE TO DRAPER CORPORATION, OF HOPEDALE, MASSACHUSETTS, A CORPORATION OF MAINE.

WEFT-END CLEARER FOR WEFT-REPLENISHING LOOMS.

Application filed November 24, 1926. Serial No. 150,542.

This invention relates to weft replenishing looms and is more particularly directed to the clearer for the weft end which leads from the discharged weft carrier to the shuttle on replenishment.

In weft replenishing looms it is now the common practice to provide means for parting or cutting the outgoing weft between the cloth selvage and the shuttle and to discharge the outgoing weft carrier or bobbin in a downward and frontward direction from the shuttle. Should the end of the parted weft remain in the shuttle eye or in the shuttle box when the outgoing weft carrier is discharged, there is danger of the weft end being carried into the shed and thereby produce imperfect cloth.

This fact has heretofore been recognized and various means have been suggested for avoiding the objections incident thereto. In some of these previous suggestions, the weft leading from the outgoing weft carrier or bobbin has been clamped between the discharged weft carrier and shuttle, so that on the pick following replenishment the weft end would be held and withdrawn from the shuttle eye, and such clamping means has comprised a fixed clamping member and a movable clamping member mounted to swing in a horizontal plane towards and from the fixed clamping member. This character of construction has involved a further uncertainty in securing or clamping the weft end, by reason of the fact that the swinging clamping member is liable to throw the weft end from between the clamping members as they are brought into clamping position.

Bearing in mind that the path of the outgoing weft carrier when it is discharged from the shuttle is in a frontward and downward direction, the present invention contemplates a weft end clearer wherein the weft end members are so related that when they are separated they present an opening which is directed upwardly and rearwardly towards the shuttle box at the moment of transfer, with the result that the opening is in the direct natural path of the weft end carrier or bobbin as it is discharged from the shuttle box.

Another important feature of the invention consists in providing the weft end clearer or clamping members with an inter-engaging projection and recess, whereby, when the weft carrier has been discharged

and the clamping members closed upon the weft between the discharged weft carrier and shuttle, it will be securely held, so that on the following pick of the shuttle it will be withdrawn from the shuttle eye.

Another important feature of the present invention consists in an apron which is mounted to extend in a position to intercept the outgoing weft carrier or bobbin in its frontward path and cause it to pass between the open jaws of the weft end clearer, the opening of which is directed upwardly and towards the lay or shuttle box.

The invention and new features thereof will best be made clear from the following description and the accompanying drawings of one good form thereof.

In the drawings:

Fig. 1 is a perspective view taken at the replenishing side of the loom showing the present invention associated therewith;

Fig. 2 is a sectional elevation from front to rear of the loom, passing through the shuttle box and apron, and showing the features of the present invention;

Fig. 3 is a detached detail in perspective showing one form of means for actuating or opening the clamping members on call for replenishment of weft;

Fig. 4 is a detailed sectional elevation showing the relation of the apron and the open clamping members as the outgoing weft carrier or bobbin is discharged from the shuttle; and

Fig. 5 is a detailed sectional elevation showing the clamping members as clamping and holding the weft end.

The loom frame 1 may be of usual construction and provided with the hopper stand 2 on which the hopper 3 may be mounted, as usual; for presenting the weft carriers successively into position for transfer. Mounted on the hopper stand is the stud or dead shaft 4 carrying the transferer 5, the hub portion of which is provided with the downwardly extending arm 6 to which is pivotally connected at 7 the usual dog 8 adapted to be engaged by a bunter 9 on the lay to effect replenishment of weft. These parts may be of usual construction.

In the present instance of the invention, the loom is shown as provided with a shuttle feeler 10 having a thread parter and clamp 11 and on call for replenishment of weft the shuttle feeler with the thread

part and clamp is moved rearwardly to part and clamp the outgoing weft end between the shuttle and cloth selvage. These parts may all be of usual and well-known construction and need no further description, the construction being such that when detection of substantial exhaustion of filling occurs by suitable detecting mechanism now well-known in the art, the shuttle feeler and thread parter and clamp will be moved rearwardly to operative position, and simultaneously therewith the dog 8 will be raised into the path of the bunter 9 to cause actuation of the transerrer on the following beat-up movement of the lay.

Mounted in suitable bearings 12 at the front of the loom is the transverse or rock shaft 13 having the rearwardly extending arm 14 for moving the shuttle feeler rearwardly on call for replenishment of filling, but as these parts are now well-known, both as to construction and mode of operation, their further description and illustration herein appears unnecessary.

The weft end clearer of the present invention is mounted on the loom frame in front of the lay and the weft end clearer members are each provided with a laterally extending arm; that is, an arm extending transversely of the lay in front of the shuttle box and in parallel relation, and the parts of the weft end clearer are so related and combined that when the laterally extending arms are separated on call for replenishment of weft, as will later appear, the opening between the laterally extending arms of the clamping members will be directed into the natural path of the weft end clearer or bobbin as it is discharged on replenishment of weft.

As shown in the present instance of the invention, a bracket 15 is secured to the loom frame, as indicated in Fig. 1, and is provided with a rearwardly extending arm 16, comprising a part of the fixed weft end clearer member. The arm 16 has extending laterally therefrom or transversely of the loom the weft end clearer arm 17 which may be additionally braced if desired by a brace member 18 secured to the under portion of the fixed weft end clearer, as at 19, and to the loom frame at 20, as indicated in Fig. 2, although this may not always be necessary.

The movable weft end clearer or clamping member, as shown in Figs. 1 and 2, is pivotally supported at the front of the loom, to partake of an opening and closing movement, and in the present instance of the invention the bracket 15 is provided with a frontwardly extending lug 21 on which is pivotally supported the movable clearer or clamping member 22, the rear end portion of which has a laterally extending arm 23 in parallel relation with the laterally extend-

ing arm 17 of the fixed clearer or clamping member, and from the construction thus far described it will be apparent that the two laterally extending arms 17 and 23 of the fixed and movable clamping or clearing members remain substantially parallel at all times. As indicated in Figs. 1 and 2, it will be seen that the fixed clearer member extends rearwardly from the front of the loom in an upwardly and rearwardly direction and that the movable clamping member 22 likewise extends rearwardly and upwardly, with the result that when the clearer members are separated on call for replenishment of weft they provide an opening between the clamping members, as indicated in Fig. 4, which is directed upwardly and rearwardly towards the lay or shuttle box in the natural path of the weft carrier as it is discharged from the shuttle.

The movable clamping member 22, in accordance with the present invention, is to be moved away from the fixed clamping member on call for replenishment of weft to provide an opening between the clearer members for the reception of the outgoing weft carrier, and to this end the movable clamping member is provided with an upwardly extending arm 24 which is rigidly secured to the movable clamping member, and at its upper portion the arm 24 has pivotally associated therewith at 25 the actuator 26 for the movable clamping member. The rear end portion of the actuator 26 extends through a slotted plate 27, as shown in Figs. 2 and 3, the slot 28 whereof is of somewhat greater vertical dimensions, as shown, than the vertical dimension of the actuator, and the actuator 26 is provided with a shoulder portion 29 rearwardly of which extends the projection 30, the construction being such that during normal weaving operations the actuator 26 will rest upon the bottom wall of the slot 28 and the clamping members of the weft clearer will remain in clamped position under the actuation of a spring 31, Fig. 1, one end of which is secured to the movable clamping member at 32, and the other end to a pin or projection 33 secured to the loom frame.

As indicated, in the present form of the invention the arm 24 is formed as part of the hub portion 34, and the movable clamping member 22 is secured to the hub portion or arm 24 by the clamping bolts 35. The details of this construction are not of special importance but that shown and described above is a good practical form of this feature.

The transverse shaft 13, as shown, Fig. 1, extends laterally beyond the bearing 12, as at 36, and has secured thereto the arm 37 from which extends a lifter 38, the lower end 39 of which underlies the actuator 26, with the result that when weft replenishment

is called and the transverse or rock shaft 13 is turned, as usual, the lifter 38 will raise the actuator 26 to position the shoulder 29 thereof for engagement with the plate 27 mounted on the lay, a condition which is indicated in Fig. 2. From the construction thus far described it will be apparent that during normal weaving operations, the actuator 26 will rest upon the lower wall of the slot 28 in the plate 27, the rearwardly extending portion 30 of the actuator affording means to prevent disengagement of the actuator from the slot in the plate. When replenishment is called, however, and the transverse shaft 13 is rocked, the lifter 38 will raise the actuator 26 in the slot 28 of the plate 27 and position the shoulder 29 for engagement by said plate as the lay moves forwardly when the shuttle has arrived in the replenishing box. As the lay moves forwardly under the conditions stated, the movable weft clamping member 22 will be lifted in an upward direction with its transverse arm 23 in parallel relation with the transverse arm 17 of the fixed clamping member, to provide an opening between the transversely extending arms which is directed upwardly and rearwardly towards the lay or shuttle box for the passage of the outgoing weft carrier. When weft replenishment has been effected and the lay moves backwardly, the actuator 26 will drop into the lower part of the slot 28 and the spring 31 will cause the movable clamping member to move to its weft end clamping position, as indicated in Fig. 1.

In weaving with certain kinds of weft it is essential that the weft thread *a* extending between the discharged weft carrier 40 and the shuttle shall be securely clamped or held, as otherwise it is liable to be pulled from between the clamping members when the shuttle is picked. In accordance with the present invention, therefore, the laterally extending arms 17 and 23 of the fixed and movable clamping members are provided with an interengaging recess and projection which effectively clamps and secures the filling end.

In the present instance of the invention, the laterally extending arm 17 of the fixed clamping member is provided with a tapering recess 41 which is adapted to receive the tapering projection 42 of the laterally extending arm 23 of the movable clamping member. The tapering recess 41 in the arm 17 is provided with friction material 43, as more clearly indicated in Figs. 4 and 5, and such friction material may be, and preferably is, felt, leather, rubber, or the like, the effect being that when the clamping members are in closed position, as indicated in Fig. 5, the weft end *a* between the discharged weft carrier and shuttle will be securely held from slipping as the shuttle is picked, and

effectively withdraw the weft end from the shuttle eye.

The lay 44 is provided with the usual shuttle box 45 having a bottom opening 46 for the passage of the outgoing weft carrier from the shuttle 47, and extending downwardly from the opening 46 is the weft carrier or bobbin chute 48 which directs the outgoing weft carrier in a downward and forward direction through the opening between the laterally extending arms 17 and 23 of the fixed and movable clamping members, which opening is directed in substantial alignment with the path of the outgoing weft carrier, as indicated in Fig. 4.

It may happen at times that the outgoing weft carrier may overthrow forwardly, and to prevent such overthrow and direct the weft carrier in its proper path to the upwardly and rearwardly extending opening between the clamping members, the present invention provides an apron, best shown in Figs. 1 and 2.

The apron 49 as shown is carried by the lay and may be conveniently secured to the front wall 50 of the shuttle box by means of securing means, such as the bolts 51. The apron is preferably, though not necessarily, formed of resilient material, such for instance, as leather or heavy fabric, which may be ordinarily sufficient to maintain the apron in its weft carrier directing position. In some cases it may be desirable to provide a spring member to act upon the apron to facilitate its response to the shock of a contacting weft carrier as it is discharged from the shuttle, and in the present instance of the invention the spring member is shown as a looped spring 52, the upper end portions of which may be secured in place by the bolts 51 which secure the apron to the lay. Where the front wall of the shuttle box 50 is formed as indicated, a filler piece 53 will be provided between the upper end of the apron and the front wall of the shuttle box to properly position the apron in the path of the outgoing filling carrier.

From the construction described as comprising a good form of the present invention, it will be apparent that the fixed and movable clamping members will remain normally closed during weaving operations until upon call for replenishment of weft they will be relatively moved to provide an opening between the laterally extending arms of the clamping members, which is directed into the natural path of the outgoing weft carrier, and on completion of replenishment of weft they will be relatively moved to clamp and hold the weft end between the discharged weft carrier and shuttle to hold it securely clamped by reason of the interengaging projection 42 of the movable clamping member and the tapering lined recess of the arm 17 of the fixed clamp-

ing member. Should the outgoing weft carrier be unduly projected forwardly on replenishment of weft, the apron will intercept the weft carrier and direct it into the opening between the clamping members.

What is claimed is:

1. A weft clearing device for weft replenishing looms, comprising a fixed weft clamping member having a weft clamping portion 10 extending in a direction transversely of the loom in front of the lay, a movable clamping member having a weft clamping portion substantially parallel to the weft clamping portion of the fixed clamping member means 15 actuated by forward movement of the lay for lifting the movable clamping member in a vertical direction away from the weft clamping portion of the fixed clamping member in parallel relation on call for replenishment to permit the discharged weft carrier to pass between the open jaws thus formed 20 by the two clamping portions, an apron mounted on the lay and extending downwardly forward of the path of the ejected weft carrier for arresting forward movement thereof and for directing the discharged weft carrier between said open jaws, and means for moving the movable clamping portion of the movable clamping member in a vertical direction towards and into engagement with the clamping portion of the fixed clamping member after the discharged weft carrier has passed between said clamping 25 portions to clamp and positively hold the weft between the shuttle and discharged weft carrier.

2. A weft clearing device for weft replenishing looms, comprising a fixed weft clamping member having a weft clamping portion 35 extending in a direction transversely of the loom in front of the lay, a movable clamping member having a weft clamping portion substantially parallel to the weft clamping portion of the fixed clamping member and 40 mounted for movement in a vertical direction away from the weft clamping portion of the fixed clamping member in parallel relation on call for replenishment to permit the discharged weft carrier to pass between the open jaws thus formed by the two clamping portions, an apron secured 45 to the front of the lay and extending downwardly forward of the path of the ejected weft carrier for arresting forward movement thereof and directing the discharged weft carrier between said open jaws, and means for moving the movable clamping portion of the movable clamping member in a vertical direction towards and into 50 engagement with the clamping portion of the fixed clamping member after the discharged weft carrier has passed between said clamping portions to clamp and positively hold the weft between the shuttle and discharged weft carrier.

3. A weft clearing device for weft replenishing looms, comprising a fixed weft clamping member having a weft clamping portion 55 extending in a direction transversely of the loom in front of the lay, a movable clamping

member having a weft clamping portion substantially parallel to the weft clamping portion of the fixed clamping member, means actuated by forward movement of the lay for lifting the movable clamping member in a vertical direction away from the weft clamping portion of the fixed clamping member in parallel relation on call for replenishment to permit the discharged weft carrier to pass between the open jaws thus formed by the two clamping portions, an apron mounted on the lay and extending downwardly forward of the path of the ejected weft carrier for arresting forward movement thereof and for directing the discharged weft carrier between said open jaws, and means for moving the movable clamping portion of the movable clamping member in a vertical direction towards and into engagement with the clamping portion of the fixed clamping member after the discharged weft carrier has passed between said clamping portions to clamp and positively hold the weft between the shuttle and discharged weft carrier.

4. A weft clearer for weft replenishing looms, comprising a fixed weft clamping member having a weft clamping arm, a movable weft clamping member having a weft clamping arm mounted for movement in parallel relation with the weft clamping arm of the fixed weft clamping member, said arms being provided the one with a wedge shaped recess and the other with an interlocking wedge projection, means actuated by forward movement of the lay for lifting the arm of the movable clamping member upwardly in parallel relation to the arm of the fixed clamping member to form an opening for the passage of the outgoing weft carrier on call for replenishment of weft, and means for moving the arm of the movable clamping member downwardly in parallel relation to the arm of the fixed clamping member to clamp the weft between the shuttle and discharged weft carrier.

5. A weft clearer for weft replenishing looms, comprising a fixed weft clamping member having a weft clamping arm, a movable weft clamping member having a weft clamping arm mounted for movement in parallel relation with the weft clamping arm of the fixed weft clamping member, said arms being provided the one with a wedge shaped recess and the other with an interlocking wedge projection, means for moving the arm of the movable clamping member upwardly in parallel relation to the arm of the fixed clamping member to form an opening for the passage of the outgoing weft carrier on call for replenishment of weft, an apron secured to the front of the lay and extending downwardly forward of the path of an ejected weft carrier for directing the outgoing weft

carrier between the open jaws formed by the two arms, and means for moving the arm of the movable clamping member in parallel relation to the arm of the fixed clamping member to clamp the weft between the shuttle and discharged weft carrier.

6. A weft clearer for weft replenishing looms, comprising a fixed weft clamping member having a weft clamping arm, a movable weft clamping member having a weft clamping arm mounted for movement in parallel relation with the weft clamping arm of the fixed weft clamping member, said arms being provided the one with a recess and the other with an interlocking projection, an actuator connected to the movable clamping member and operated by frontward movement of the lay for lifting the arm of the movable clamping member in parallel relation to the arm of the fixed clamping member to form an opening for the passage of the outgoing weft carrier on call for replenishment of weft, an apron mounted on the lay in front of the path of the outgoing weft carrier to direct it between the two arms, and means for moving the arm of the movable clamping member in parallel relation to the arm of the fixed clamping member to clamp the weft between the shuttle and discharged weft carrier.

7. A weft clearer for weft replenishing looms, comprising a fixed weft clamping member having a weft clamping arm, a movable weft clamping member having a weft clamping arm, means actuated by the lay for lifting the movable clamping member on an upwardly extending arc in parallel relation with the weft clamping arm of the fixed weft clamping member, said arms being provided the one with a wedge shaped recess and the other with an interlocking wedge projection, and means for moving the arm of the movable clamping member in parallel relation to the arm of the fixed clamping member to clamp the weft between the shuttle and discharged weft carrier.

8. A weft clearer for weft replenishing looms, comprising two clamping members each having a weft clamping arm extending transversely of the loom and in parallel relation, one having a wedge shaped recess and the other a wedge shaped projection to engage the recess to clamp and hold the weft thread, means actuated by frontward movement of the lay for relatively moving the clamping members in an upwardly extending path on call for replenishment of weft to present an opening directed towards the lay for the passage of the outgoing weft carrier, and means for relatively moving the clamping members to close said opening and clamp the thread between the discharged weft carrier and shuttle.

9. A weft clearer for weft replenishing looms, comprising two clamping members

each having a weft clamping arm extending transversely of the loom and in parallel relation, one having a wedge shaped recess lined with friction material and the other a wedge shaped projection to engage the recess to clamp and hold the weft thread, means for relatively moving the clamping members in an upwardly extending path on call for replenishment of weft to present an opening directed towards the lay for the passage of the outgoing weft carrier, an apron secured to the front of the lay and projecting downwardly frontward of the path of an ejected weft carrier for directing the outgoing weft carrier through said opening, and means for relatively moving the clamping members to close said opening and clamp the thread between the discharged weft carrier and shuttle.

10. A weft clearer for weft replenishing looms, comprising two clamping members each having a weft clamping arm extending transversely of the loom and in parallel relation, one having a recess and the other a projection to engage the recess to clamp and hold the weft thread, means for relatively moving the clamping members in an upwardly extending path on call for replenishment of weft to present an opening directed towards the lay for the passage of the outgoing weft carrier, an apron mounted on the lay in front of the path of the outgoing weft carrier to arrest frontward movement of the ejected weft carrier and direct it through said opening, and means for relatively moving the clamping members to close said opening and clamp the thread between the discharged weft carrier and shuttle.

11. A weft clearer for weft replenishing looms, comprising two weft clamping members supported by the loom frame frontward of the lay and each having a clamping arm extending transversely of the loom in parallel relation when in either opened or closed position, means for relatively swinging said members in a vertical direction to present an opening between the parallel clamping arms of said members directed towards the shuttle box for the passage of the outgoing weft carrier on replenishment of weft and to close said opening and clamp the weft between the shuttle box and discharged weft carrier and a flexible apron mounted upon the front of the lay and extending downwardly in front of the path of movement of the ejected weft carrier to direct it between the parallel clamping arms of the two clamping members.

12. A weft clearer for weft replenishing looms, comprising two weft clamping members each having an arm extending transversely of the loom in parallel relation, means for relatively swinging said members about a centre to present an opening between the arms of said members directed towards the shuttle box for the passage of the out-

- going weft carrier on replenishment of weft, an apron secured to the front of the lay and extending downwardly frontward of the path of an ejected weft carrier for arresting its forward movement and for directing the outgoing weft carrier through said opening and to close said opening and clamp the weft between the shuttle box and discharged weft carrier.
- 10 13. In a weft replenishing loom, the combination of the lay having a shuttle box, and an apron mounted on the front of the lay and extending in a downward direction frontward of the path of an ejected weft carrier for arresting its forward move-
- ment and for directing an outgoing weft carrier in desired direction.
14. In a weft replenishing loom, the combination of the lay having a shuttle box provided with an opening for the passage of a weft carrier on replenishment of weft, and an apron mounted on the lay in front of the shuttle box and extending downwardly frontward of the path of an ejected weft carrier for arresting its forward movement and for directing the path of movement of an outgoing weft carrier.

In testimony whereof, I have signed my name to this specification.

PATRICK KEEGAN.
